CURTAIN ROD PACKAGE

David W. Smith, Freeport, Ill., assignor to Western Newell Mfg. Co., Freeport, Ill., a corporation of Illinois

Filed July 13, 1964, Ser. No. 80,838

Term of patent 14 years

(Cl. D58—2)

FIG. 2 is a perspective view as seen from the opposite side of the package.

FIG. 3 is an enlarged sectional view taken along the line 3—3 in FIG. 1.

FIG. 4 is an enlarged fragmentary sectional view taken along the line 4—4 in FIG. 3.

I claim:

The ornamental design for a curtain rod package, substantially as shown.
